UNITED STATES PATENT OFFICE.

ARTHUR D. PETTIBONE, OF CLEVELAND, OHIO, ASSIGNOR TO THE B. L. MARBLE CHAIR COMPANY, OF BEDFORD, OHIO.

DESIGN FOR AN ADJUSTING WHEEL FOR CHAIR IRONS.

Application filed October 18, 1921. Serial No. 508,626. Term of patent 14 years.

To all whom it may concern:

Be it known that I, ARTHUR D. PETTIBONE, a citizen of the United States, residing at Cleveland, in the county of Cuyahoga and State of Ohio, have invented a new, original, and ornamental Design for an Adjusting Wheel for Chair Irons, of which the following is a specification, reference being had to the accompanying drawing forming part thereof.

Figure 1 is a plan view.

Figure 2 is a side elevation.

Figure 3 is a bottom plan view.

I claim:

The ornamental design for an adjusting wheel for chair irons, as shown.

In testimony that I claim the foregoing I have hereunto set my hand at Cleveland, in the county of Cuyahoga and State of Ohio.

ARTHUR D. PETTIBONE.
